Inventor:

R. A. Houghton.

Thos J. Sprague

UNITED STATES PATENT OFFICE.

RUFUS A. HOUGHTON, OF DEFIANCE, OHIO.

RAILWAY.

SPECIFICATION forming part of Letters Patent No. 296,411, dated April 8, 1884.

Application filed October 1, 1883. (No model.)

To all whom it may concern:

Be it known that I, RUFUS A. HOUGHTON, of Defiance, in the county of Defiance and State of Ohio, have invented new and useful Improvements in Railways; and I do hereby declare that the following is a full, clear, and exact description thereof, reference being had to the accompanying drawing, which forms a part of this specification.

10 This invention relates to certain new and useful improvements in the construction of railways; and the invention consists in the peculiar construction, arrangement, and combination of the various parts, all as more fully 15 hereinafter set forth.

It has heretofore been proposed to construct rail-chairs with a base-plate having a hook on one side to embrace the foot of the rail and an intermediate plate, said plate having a hook 20 on its opposite end, also to embrace the foot of the rail; but such chairs have the disadvantage of having the base-plate thinnest at that point where the greatest strain occurs, and consequently increases the leverage of the hook by 25 reason of the increased thickness of the intermediate plate at the edge, where it is embraced by the hook, thus rendering said plate more susceptible to fracture, which objections it is the object of my invention to overcome. This

30 I accomplish by making the bed-plate, as well as the intermediate plate, with the greater bulk of the metal directly opposite the hook, or at that point where the greatest amount of strain is likely to occur, and having the hook which 35 projects from the base-plate of the shortest length possible consistent with the strength of the device, all as more fully hereinafter set forth in the following description, and shown in the drawing, in which the drawing represents a cross-section of a rail provided with 40 my improved bed plate or seat.

In the accompanying drawing, which forms a part of this specification, A represents the rail which is designed to be rigidly secured to the ties.

45 C represents a metallic bed-plate of any desired and proper length, and is provided with the upwardly-projecting hook-flange c. The upper face of this bed-plate C has a portion,

c', extending parallel with its under face to a line formed by its junction with a vertical plane passing through the center of the rail, and from said line it inclines downward, as shown at b, till it reaches a point directly opposite the foot of the rail, when it again extends in a horizontal plane parallel with its under face, in this manner forming a broken surface. Upon this bed C rests the intermediate plate, B, which is likewise provided with the upwardly-projecting hook-flange d, 60 the under face of this intermediate plate, B, being in shape to conform to the upper face of the bed C.

In practice, the two plates C B are placed upon the ties, as shown, their hooked flanges 65 embracing the foot of the rail, the parts being held to place by spikes D E, the former of which may pass through slots a in the edge of the plate C, which projects beyond the plate B, as shown, such spikes being driven so as to 70 force the hooked flanges d c toward each other and compel them to firmly grasp the foot of the rail. By this construction of parts I provide an interlocking device for securing the rail in place, which can readily be laid so as 75 to break joints, while the employment of fish-plates and bolts, as generally used, is dispensed with.

It is evident that the foot of the plate B may be formed so as to overlap the inner edge of 80 the bed-plate C, dispensing with the holes a, without departing from the spirit of my invention.

What I claim as my invention is—

1. A base and support for railway-rails, and 85 as a means for securing the same upon the ties, the bed-plate C and intermediate plate, B, each provided with a projecting hook, as described, said plates constructed with the greater bulk or thickness of metal directly opposite 90 said hooks, substantially as and for the purpose set forth.

2. In combination with the rail A, the intermediate plate, B, and bed-plate C, adapted to grasp the foot of the rail, said plate constructed with a broken upper surface, substantially as described.

3. In combination with the rail A, and as

means for securing the same upon the ties, the bed-plate C, provided with the opening a, incline surface b, horizontal plane c', and the hook c, and intermediate plate, B, having hook 5 d, and an under face substantially conforming to the upper face of the plate C, as set forth, whereby the inner end of the said plate B is thinnest and the shank of the hook c is made

of a minimum length, substantially as and for the purpose set forth.

RUFUS A. HOUGHTON.
